DESIGN FOR A DRESS ENSEMBLE

Stella Brownie Kaufman, New York, N. Y.

Application July 22, 1941, Serial No. 102,341

Term of patent 3½ years

To all whom it may concern:

Be it known that I, Stella Brownie Kaufman, a citizen of the United States, residing in New York city, in the county of New York and State of New York, have invented a new, original, and ornamental Design for a Dress Ensemble, of which the following is a specification, reference being had to the accompanying drawings, forming part thereof.

The characteristic feature of my design resides in the combination on the dress ensemble disclosed of the specific jacket member embroidered as shown.

I claim:

The ornamental design for a dress ensemble, substantially as shown and described.

STELLA BROWNIE KAUFMAN.
